GRINDING DEVICE

Application filed December 31, 1931. Serial No. 584,154.

The present invention relates broadly to grinding devices and more especially to a grinding apparatus adapted for grinding detachable bits for drilling rock.

5 Rock drill bits comprise short detachable members adapted to be mounted on the working end of a rock drill and after the bit is dulled to the limit of its useful life, it is the present custom to abandon the point and 10 replace it by a new one. The present invention contemplates reclaiming these abandoned points by providing a simple holder for a bit which will automatically correctly present the drill faces to a grinding wheel 15 whereby the cutting edges of the drill bit may be restored to a useful condition. Drill bits are made in various sizes and the drill heads are standardized relative to the size of the shank or thread portion of the bit. 20 For example, one-inch threaded bits are provided with drill heads of the sizes which differ by eighth inch intervals between the sizes two and one quarter inches to one and five eighths inches. Other larger or smaller 25 shanks carry proportionally ranged head sizes. It is the purpose of the present invention to provide means whereby the larger standard sizes may be ground into the next smaller standard size and thereby provide substantially increased utility for abandoned or discarded drill bits.

In accordance with the present invention, the drill bit is locked in a predetermined fixed position in a holder. This holder is 35 adapted to cooperate in definite fixed relation with a tool rest which may be moved toward the face of a grinding wheel at such position and angle as to properly grind one set of faces on a drill bit. The tool rest is 40 then adjusted to present a new supporting face for the tool holder so that the remaining sides of the drill bit may be ground to provide suitable cutting edges. The ends of the cutting faces are usually worn away during 45 the use of the bit, and, therefore, a third tool

holding face is provided which properly positions the side of the bit for grinding the over-all dimension of the bit to size, thereby bringing the outer corners of the faces to the proper sharp formation. In order to facilitate the grinding operations, the tool rest is adapted to be brought against an adjustable stop so that the amount of grinding taking place at each operation is definitely controlled whereby relatively unskilled labor 50 may be utilized for the grinding operations.

It is recognized that the present inventions may be embodied in constructions other than those specifically disclosed herewith and, therefore, the present disclosure is to be 60 understood as illustrative and not in the limiting sense.

Fig. 1 is a front elevational view of a grinding wheel with the tool rest mounted in front of the wheel to properly address a 65 drill bit to the face of the wheel.

Fig. 2 is a side elevational view of the construction shown in Fig. 1.

Fig. 3 is a plan view of the face of a bit ground in accordance with the present invention.

Fig. 4 is an elevational view of the bit shown in Fig. 3.

Fig. 5 is an end view of a bit tool holder.

Fig. 6 is a side view of the device shown in 75 Fig. 5.

Fig. 7 is a plan view of a jig for setting a bit in the tool holder prior to the grinding operations.

Fig. 8 is a front elevational view of the jig 80 shown in Fig. 7.

Fig. 9 is a cross-section on line 9-9 of Fig. 2.

Referring to the drawings and more especially to Figs. 1 and 2, a grinding wheel 1 85 is mounted upon a spindle 2 which connects with driving mechanism common in the art for rotating grinding wheels. A portion of the frame 4 of the grinder may be provided with a bracket 5 on which a supporting arm 90

6 is secured by stub bolts 7. This supporting arm 6 carries a supporting shaft 8 which preferably is provided with a shoulder 9 and a nut 10 carried by the outer end of the supporting shaft 8 is adapted to clamp the shaft 8 tightly in position in the supporting arm 6. This supporting shaft 8 is provided in the forward portion with an opening 11 extending axially of the shaft and a pair of slots 12 are cut through diametrically opposite sides of the shaft 8 adjacent the inner end of the opening 11. A slide rod 14 is mounted for reciprocating movement in the opening 11 and carries a cross pin 15 which passes through the slots 12 and through diametrical opposite sides of a stop collar 16 so that when the slide rod 14 is moved endwise in the opening 11, the stop collar is correspondingly slid along the supporting shaft 8. The forward end of the slide rod 14 is screw threaded and engages the screw threads in a rotatable sleeve 17 which carries a knurled head 18. The rotatable sleeve 17 may be provided with an annular groove 19 into which the end of a guide screw 20 extends so that the rotatable sleeve is locked for rotation in the end of the supporting shaft 8. A work rest 21 is slidably and normally rotatively mounted on the outer end of the supporting shaft 8. This work rest is provided with two pairs of supporting faces 22, 24 and 25, 26. Preferably, stop pins 27 and 28 are arranged on the supporting faces 22 and 25 adjacent the side next to the grinding wheel 1. The planes 35 of each pair of these supporting faces 22, 24, and 25, 26 meet at substantially right angles to receive a substantially square cross-sectional tool holder. The planes of the faces 22, 24 meet in a line that is inclined upwardly relatively to the face of the grinding wheel 1 and inwardly toward the axis of this grinding wheel. The planes of the faces 25, 26 meet in a line that is inclined downwardly relative to the face of the grinding wheel 1 and also inwardly toward the axis thereof. The work slide 21 is provided with four keyways 29, 30, 31, and 32, which are adapted to cooperate with a short key 34 fixedly mounted in the supporting shaft 8. It will be observed that by moving the work slide 21 toward the knurled head 18, a sufficient distance to clear the short key 34, that the work slide may be rotated on the supporting shaft 8 to bring any one of the four keyways into cooperation with the short key 34. A pair of supporting faces 35, 36 meeting at right angles, are provided on the side of the work slide 21 and it will be noted that the supporting face 36 comprises a plane which is angularly disposed to the face of the grinding wheel 1.

The keyways 29, 30, 31, and 32 are slightly wider than the short key 34 so that the work rest may be given a limited rotative oscillatory movement when the grinding is be-

ing done to smooth the work, to prevent undue local wear on the wheel, and also to prevent burning the work. When the respective keyways engage the short key 34, the following work faces are positioned in operative relation to the grinding wheel; keyway 29 positions supporting faces 22, 24; for grinding one set of faces of the drill bit cutting edges; keyway 30 positions faces 35 and 36 to grind the ends of the cutting edges; keyway 31 positions the faces 25, 26 to grind the other set of faces of the cutting edges; and keyway 31 holds the work rest in neutral position to permit the use of a grinding wheel trueing device.

Figs. 3 and 4 illustrate a drill bit 37 which has been ground upon the apparatus described, and wherein the planes of the side of a cutting edge are designated by the planes A and B while the diametrical dimension of the bit is designated as C.

Figs. 5 and 6 illustrate a tool holder 38 substantially square in cross-section and with a longitudinal opening 39 coaxial with the axis of the tool holder. The shank of the drill bit 37 is adapted to fit the opening 39 and to be clamped therein by means of set screws 40.

Figs. 7 and 8 illustrate a jig for correctly positioning the drill bit 37 in the tool holder 38. This jig comprises a base 41 having a crossed opening 42 provided therein. A web 44 extends from one edge of the base in a vertical direction and a guide head 45 extends from the web 44 substantially parallel to the base 41. The guide head 45 is provided with an opening 46 which is substantially equal to the cross-sectional dimension of the tool holder 38.

In the operation of the device, a drill bit 37 is set on the base 41 of the jig with the cutting edges of the bit setting in the crossed opening 42 of the jig. The tool holder 38 is slipped into the opening 46 of the jig and over the shank of the drill bit 37 in the jig. The set screws 40 are tightened and the drill bit is now locked in the tool holder with the cutting edges of the bit definitely positioned relative to the sides of the tool holder. The tool holder is now placed against the supporting faces 22, 24 on the work rest 21 with the forward end of the tool holder in contact with the stop pin 27, which prevents the drill bit from being drawn into the face of the grinding wheel. The work rest is now slid forwardly on the shaft 8 over the key 34 toward the face of the rotating grinding wheel 1 and the wheel operates to grind one face of the bit on the angle indicated by the plane A of Fig. 4. When the bit is dulled, before the grinding operation, the cutting edges are worn down to be substantially flat tops and the first grinding operation is continued until the grinding wheel cuts away the metal to substantially the middle part of the dulled

flattened edge. When this point in grinding has been reached, the knurled head 18 is rotated to bring the stop collar 16 against the front end of the work rest, thereby limiting the forward movement of the work rest toward the grinding wheel. The tool holder 38 is then turned through 90° with the front end thereof against stop pin 27 and the work rest is moved toward the grinding wheel 5 until stopped by the stop collar 16, thus grinding a second face on the drill bit. After the cutting edges have all been ground on one face or side, then the work rest 21 is moved outwardly toward the knurled nut 18 to clear the key 34 and the work rest is turned 15 through 180° and then moved inwardly so that the key 34 now engages the keyway 31, thereby bringing the supporting faces 25, 26 into operation. The tool holder as now positioned on the supporting faces 25, 26, is 20 brought in contact with the stop pin 29 which prevents the work from sliding into the wheel, and the work holder is moved toward the rotating grinding wheel until the work 25 holder is stopped by the collar 16. The work holder is again turned through 90° and the grinding operation is continued to grind the faces indicated by the plane B of Fig. 4. Even after the flat tops or edges of the bit 30 have been brought to a sharp edge, the outer ends of the edges are usually defaced so that it becomes desirable to grind the bit on the dimension C shown in Fig. 3. A proper adjustment for the stop collar 16 is made. The work rest is turned through 90° so that the 35 short key 34 engages the keyway 30, thereby bringing the supporting faces 35 and 36 on top of the work rest. The tool holder 38 is brought into contact with the supporting faces, 35, 36 and with the end of the tool 40 holder against the stop pin 47. The work rest 21 is now moved toward the face of the rotating grinding wheel 1 and the ends of the cutting faces on the drill bit 37 are ground away 45 until the work rest 21 is stopped by the stop collar 16. This reduces the diameter of the bit to the proper dimension.

It will be observed that the supporting face 36 is angularly disposed to the face of the 50 grinding wheel 1 so that the ends of the cutting edges of the bit 37 are properly undercut during the grinding operation.

From the foregoing, it will be observed 55 that the present invention provides a rigid, at the same time simple, tool by which drill bits may be sharpened by relatively unskilled labor, and wherein the parts are so constructed that the critical angles to be ground are automatically provided for.

60 What I claim is:—

1. A grinding device for drill bits comprising a grinding wheel, guiding means, a work rest mounted for reciprocatory movement on said guiding means, said work rest 65 comprising a plurality of pairs of support-

ing surfaces inclined relative to the face of the grinding wheel, one of said pair of surfaces being inclined in one direction toward the face of said wheel and the other of said pair of surfaces being inclined in the opposite 70 direction toward the face of said wheel, and a work holder cooperative with said work rest to present a drill bit to said grinding wheel.

2. A grinding device for drill bits comprising 75 a grinding wheel, guiding means, a work rest mounted for reciprocatory movement on said guiding means, an adjustable stop to limit the movement of said rest toward the grinding wheel, said work rest comprising a plurality of pairs of supporting surfaces inclined relative to the face of the grinding wheel, one of said pair of surfaces being inclined in one direction toward the face of said wheel and the other of said pair of surfaces 80 being inclined in the opposite direction toward the face of said wheel, and a work holder cooperative with said work rest to present a drill bit to said grinding wheel.

3. A drill bit grinder comprising a grinding wheel, guiding means, a work rest slidably and rotatively mounted on said guiding means, said work rest having a plurality of supporting surfaces, a bit holder adapted to cooperate with the supporting surfaces on 85 said work rest to present a drill bit to the work face of the grinding wheel, said bit holder comprising a separate block unattached relative to the work rest, and a stop to limit the movement of said work rest towards said grinding wheel.

4. A drill bit grinder comprising a grinding wheel, guiding means comprising a shaft, a work rest slidably and rotatively mounted 90 on said guiding means, said work rest having a plurality of pairs of angularly disposed supporting surfaces, a bit holder adapted to cooperate with the supporting surfaces on 95 said work rest to present a drill bit to the work face of the grinding wheel, a stop to limit the movement of the tool holder on said surfaces, and an adjustable stop to limit the movement of said work rest towards said grinding wheel.

5. A drill bit grinder comprising a grinding wheel, guiding means, a work rest slidably and rotatively mounted on said guiding means, a plurality of supporting surfaces on 100 said work rest, means to retain said work rest in a predetermined rotative position on said guiding means to render a predetermined supporting surface effective relative to said grinding wheel, a tool holder adapted to hold the drill bit to be ground and to cooperate with the supporting face on the work rest 105 to present cutting edges on the drill bit to the grinding wheel for grinding, and an adjustable stop to limit the movement of said work rest toward the grinding wheel.

6. A drill bit grinder comprising a grind-

ing wheel, a supporting shaft, a work rest slidably and rotatively mounted on said shaft, a plurality of pairs of right angularly disposed supporting surfaces on said work rest, means to retain said work rest in a predetermined rotative position on said guiding means to render a predetermined pair of supporting surfaces effective relative to said grinding wheel, a tool holder adapted to hold the drill bit to be ground and having right angularly disposed surfaces to cooperate with the supporting face on the work rest to present cutting edges on the drill bit to the grinding wheel for grinding, an adjustable stop to limit the movement of said work rest toward the grinding wheel, and means extending through said shaft to adjust said stop.

7. A drill bit grinder comprising a grinding wheel, guiding means adjacent said grinding wheel, a work rest slidably mounted on said guiding means, said work rest comprising a plurality of supporting surfaces angularly disposed to the plane of the face of the grinding wheel, said supporting surfaces being arranged in pairs with one pair of supporting surfaces meeting at a line which is inclined upwardly and inwardly relative to the plane of rotation of the face of the grinding wheel, and another pair of supporting surfaces meeting at a line inclined downwardly and inwardly relative to said wheel face, a work holder adapted to hold a drill bit, said work holder having adjacent sides of the same angular relation as the adjacent surfaces on the work rest whereby the surfaces on the work holder are adapted to cooperate with the surfaces on the work rest to properly present the faces of a drill bit to the grinding wheel for grinding.

40 8. A drill bit grinder comprising a grinding wheel, guiding means adjacent said grinding wheel, a work rest slidably mounted on said guiding means, a stop to limit the movement of the work rest, said work rest comprising a plurality of supporting surfaces angularly disposed to the plane of the face of the grinding wheel, said supporting surfaces being arranged in pairs with one pair of supporting surfaces meeting at a right angle in a line which is inclined upwardly and inwardly relative to the plane of rotation of the face of the grinding wheel, a work holder adapted to hold a drill bit and with the side surfaces of said holder meeting at right angles, said work holder being an independent block unattached to said work rest and with the surfaces on the work holder adapted to cooperate with the surfaces on the work rest to properly present the faces of a drill bit to the grinding wheel for grinding.

9. Devices for grinding drill bits comprising a tool holder comprising an independent block having supporting side surfaces and with a longitudinal opening to receive a drill bit, means to position the direction

of extent of the cutting edges of the drill bit relatively to the said surfaces, a grinding wheel, means cooperating with said surfaces on the tool holder to present said cutting edges of the drill bit to the grinding wheel to sharpen said edges.

10. A grinding device for drill bits comprising a grinding wheel, a bracket, a supporting shaft carried by said bracket, a work rest mounted for reciprocatory movement on said shaft, said work rest comprising a plurality of pairs of supporting surfaces inclined relative to the face of the grinding wheel, one of said pair of surfaces being inclined in one direction toward the face of said wheel and the other of said pair of surfaces being inclined in the opposite direction toward the face of said wheel, a work holder having right angularly disposed surfaces cooperating with said work rest to present a drill bit to said grinding wheel, and means to guide a drill bit into a definite predetermined relation to said work holder.

11. A drill bit grinder comprising a grinding wheel, guiding means, a work rest slidably and rotatively mounted on said guiding means, said work rest having a plurality of supporting surfaces, a bit holder adapted to cooperate with the supporting surfaces on said work rest to present a drill bit to the work face of the grinding wheel, said bit holder having a longitudinal opening to receive the shank of a drill bit, means to set a drill bit in the said opening with the lines of the cutting edges at right angles to the surfaces on the work rest, and a stop to limit the movement of said work rest towards said grinding wheel.

12. A drill bit grinder comprising a grinding wheel, supporting means, a work rest rotatively mounted on said supporting means, a plurality of supporting surfaces on said work rest, means to retain said work rest in a predetermined rotative position on said supporting means to render a predetermined supporting surface effective relative to said grinding wheel, a tool holder adapted to hold the drill bit to be ground and to cooperate with the supporting face on the work rest to present cutting edges on the drill bit to the grinding wheel for grinding, and an adjustable stop mounted on said supporting means to limit the movement of said work rest toward the grinding wheel.

13. A drill bit grinder comprising a grinding wheel, a tool holder support, a tool holder adapted to hold the drill bit to be ground, said tool holder having a longitudinal opening in which the drill bit may be rotated, means to set a drill bit into said tool holder with the edges of said bit set to cause said tool holder to present cutting edges on the drill bit to the grinding wheel for correct grinding, means to lock the drill bit in the holder, and an adjust-

able stop to limit the movement of said tool holder toward the grinding wheel.

14. A drill bit grinder comprising a grinding wheel, a work rest slidably mounted for movement toward and from said wheel, said work rest comprising a plurality of supporting surfaces angularly disposed to the plane of the face of the grinding wheel, means on said work rest to direct a drill bit upwardly and inwardly relative to the plane of rotation of the face of the grinding wheel, and another means on said work rest to direct said drill bit downwardly and inwardly relative to said wheel face, and stop means to limit the movement of said drill bit toward said grinding wheel.
